UNITED STATES PATENT OFFICE.

MUNSON H. TREADWELL, OF NEW YORK, N. Y.

LADLE.

No. 856,744.

Specification of Letters Patent.

Patented June 11, 1907.

Application filed June 27, 1906. Serial No. 323,572.

To all whom it may concern:

Be it known that I, MUNSON H. TREADWELL, a citizen of the United States, residing at New York, in the county of New York and State of New York, have invented certain new and useful Improvements in Ladles, of which the following is a full, clear, and exact specification.

This invention relates to ladles, and more particularly to slag ladles for use in connection with blast furnaces, foundries and the like.

The object of the invention is to provide a ladle in which the liability to breakage, due to unequal expansion, is reduced to a minimum, and in which should breakage occur, notwithstanding precautions taken to prevent the same, the broken part may be easily replaced, without necessarily interfering with the continued use of the other parts.

In carrying out my invention, I provide means whereby that portion of the ladle which is especially subject to breakage by reason of unequal expansion of another portion is not injuriously affected by such expansion, and further provide means whereby the various parts, including the bottom, may be easily renewed. More particularly, I provide a sectional ladle, the rim portion of which is sectional and expandable, and the bottom portion of which is removable. I further provide means whereby in a ladle of this general character, the contents are prevented from adhering to the ladle.

The invention further comprises improvements in the form, arrangement and construction of parts, all of which will be more fully described in connection with the accompanying drawings, wherein

Figure 1 is an elevation, partly in section; Fig. 2 is a plan view; Fig. 3 shows the ladle mounted on a truck; and Figs. 4, 5 and 6 are detail views, and Fig. 7, shows a modification.

1 represents the bottom, shaped similarly to a bowl, and is made somewhat thicker at the lower portion. The upper edge has a grooved, circumferential flange 2, within which the lower side of the intermediate annular section 3 fits.

4, 4, represent lugs, through which bolts 5 pass to securely attach the sections.

The inner diameter of the annular intermediate section 3 is slightly larger than that of the bottom section, so as to form a shoulder 6, and the function of this shoulder is to permit the slag or cinder to be freely dis-

charged from the ladle, when cooled, by preventing the mass from flowing in between the sections and adhering thereto. The intermediate section carries a number of pairs of lugs 8, to which a ring 9, carrying trunnions 10, is fastened, so as to permit the ladle to be mounted on a truck. In smaller portable sizes, instead of trunnions, long handles may be used. The intermediate sections 65 may be channeled at the top, similarly to the bottom section if desired, and the next section made to fit therein, or lugs may also be used for this purpose. While the drawings show but one intermediate section, it 70 will be obvious that more than one may be used in the same manner, without departing from the invention.

The upper side of the intermediate section has a flange 13, with radial slots 14 therein, 75 and the segments 15, forming the top section, have flanges 16, with slots 17 therein at right angles to the slots 14, and through these slots pass bolts 18, which are set firmly to hold the segments 15 in engagement with 80 the upper edge of the intermediate section. By providing these slots at right angles, the assembly of the parts is facilitated, and also the substitution of a new part for a damaged one. It will also be noted that the segments 85 are of larger diameter than the intermediate or bottom section, so as to prevent lodgment of the liquid or solidified material. The segments 15 carry lugs 20, through which bolts 21 pass to loosely secure the segments together, so that they can expand and contract with changes in temperature. The space 23 formed between the sections 1 and 3 may be filled with fire clay, in order to prevent leakage of molten material.

26 represents a truck, which may be of any desirable construction, and carrying supports to receive the trunnions 10, thereby permitting the ladle to be tipped to discharge the contents. It will be understood, however, that I do not restrict the invention to this class of ladles, as my improvements are also applicable to so-called "stopper" ladles, etc. For some ladles, the intermediate and bottom sections may be made in one piece, and the expandable top secured directly thereto, as shown in Fig. 7.

As applied to large ladles, of a ton or more capacity, my invention effects a considerable economy in maintenance. Notwithstanding the various kinds of linings which have been proposed for slag ladles, they are

subject to deterioration and frequently burn out and furthermore crack very quickly. By the use of this invention, any part can be easily renewed or repaired without involving renewal of the entire ladle. Another and very important cause of deterioration is that when the ladles are in use they are not often filled to the top, on account of the variance of the slag supply. In a case of this kind, 5 the lower portion of a bowl made in one piece will expand in the lower part, putting such a strain upon the upper portion as to cause the same to fracture or break. It is also a fact, that the top of the slag, even 10 when the pot has been filled completely, will cool off before the main body. It can readily be seen that this operation will have the same effect upon the pot, as when it is not completely filled. By providing an expandable rim, as before described, all danger of fracturing the top of the ladle is avoided. 15 Also where the rim burns away, it can be renewed section by section, as necessary.

From the foregoing description it can be 20 seen that a sectional ladle built according to my invention can be advantageously constructed of as many cast sections as may be desired, and that the parts can be easily renewed. Suitable refractory linings may be 25 used where necessary.

Modifications and changes may be made in the specific construction described, without departing from the scope of the invention, and the terms used herein are not to be 30 narrowly construed.

Having thus described my invention, I declare that what I claim as new and desire to secure by Letters Patent, is,—

1. A ladle comprising a bottom portion 40 and a sectional rim carried thereby and varying in diameter according to changes in the diameter of the bottom portion, substantially as described.

2. A ladle comprising a bottom, an annular section, and a sectional rim mounted on said annular section and varying in diameter with changes in the diameter of the annular section, substantially as described.

3. A ladle comprising a plurality of horizontal sections secured together, the sections at their meeting edges being of different diameters, and the upper section varying in diameter according to changes in diameter of the adjacent section, substantially as described.

4. A ladle comprising a plurality of sections secured together, the sections at their meeting edges being of different diameters to form shoulders, and the top section comprising a plurality of segments secured together, substantially as described.

5. A ladle comprising a plurality of sections secured together, the sections at their meeting edges being of different diameters to form shoulders, and the top section comprising

85
ing a plurality of segments secured together to permit expansion, substantially as described.

6. A ladle comprising a bottom having a channel in its upper edge, and a second section secured to said bottom and fitting in said channel, said second section being of greater diameter than said bottom section, substantially as described.

7. In a ladle, a bottom, and an expandible top section secured thereto, the bottom section projecting inwardly from the surface of the top section, substantially as described.

8. A ladle comprising a bowl-shaped bottom section, an annular intermediate section, and a sectional rim or top constructed to vary in diameter according to changes in the diameter of the annular section, said annular section carrying supporting means, substantially as described.

9. A ladle comprising a bottom section having a flange, and an expandible top section having a flange, and means for securing said sections together to permit movement of said top section relatively to said bottom section, substantially as described.

10. A ladle comprising a bowl-shaped bottom section, an annular intermediate section, and a sectional rim carried by said annular section and varying in diameter according to changes in the diameter of the annular section, supporting means carried by said annular section, and a truck having means engaging said supporting means, substantially as described.

11. A ladle comprising a continuous bottom portion varying in diameter with changes in temperature, and a top portion composed of segments free to expand and contract with the bottom portion, as the latter responds to changes in temperature, substantially as described.

12. A ladle comprising a bottom portion, an intermediate portion carrying said bottom portion and an upper portion, trunnions carried by the intermediate portion, said upper portion changing in diameter according to changes in the diameter of the intermediate portion, substantially as described.

13. A ladle adapted to be supported in trunnions and comprising a bottom portion carrying supports, and a top portion carried thereby and comprising sections loosely bolted together, said sections at their meeting edges being of different diameters, substantially as described.

14. A ladle comprising a removable bottom portion, a flanged sectional top portion varying in diameter according to changes in the diameter of the bottom section, and trunnions carried by one of said sections, substantially as described.

15. A ladle comprising a removable bottom portion, an annular supporting portion carrying said bottom portion, and a top com-

posed of segments bolted to said supporting section and varying in diameter according to changes in diameter of said bottom and said annular supporting section, substantially as described.

16. A ladle composed of a plurality of sections one supporting another, one of the supported sections being constructed to vary in diameter according to changes in diameter of its supporting section, substantially as described.

17. A ladle composed of annular sections rigidly bolted together, one of said sections being composed of a plurality of segments independently mounted on the adjacent section and constructed to vary in diameter according to changes in diameter of the adjacent supporting section, substantially as described.

18. A ladle composed of horizontal sections one supporting another, the upper of said sections being composed of segments independently secured to the underlying section and loosely connected to each other in such manner as to vary in diameter according to changes in the diameter of the section carrying said segments, substantially as described.

19. In a ladle, the combination with a section carrying radially slotted lugs, of a second section having a transversely extending slotted lug, and a bolt passing through said slots to secure said sections together, substantially as described.

20. In a ladle, the combination with a section carrying radially slotted lugs, of a second section engaging said first section and having a transversely extending slotted lug, and a bolt passing through said slots and securing the ends of said sections together, substantially as described.

21. In a ladle, the combination with a bowl-shaped section carrying radially slotted lugs, of a second segmental section engaging said first section and having a transversely extending slotted lug, and a bolt passing through said slots and securing the ends of said sections together, substantially as described.

In testimony whereof I affix my signature, in presence of two witnesses.
